UNITED STATES PATENT OFFICE.

EDMUND L. SUESS, OF PITTSBURGH, PENNSYLVANIA.

SPARK-PLUG.

1,220,472.

Specification of Letters Patent. Patented Mar. 27, 1917.

Application filed March 8, 1916. Serial No. 82,831.

To all whom it may concern:

Be it known that I, EDMUND L. SUESS, a citizen of the United States, residing at Pittsburgh, in the county of Allegheny and 5 State of Pennsylvania, have invented certain new and useful Improvements in Spark-Plugs, of which the following is a specification.

This invention relates to spark plugs having two spark gaps, one of which is on the outside of the engine cylinder so that the operation of the plug may be observed and any defects readily detected.

The invention has for its object to provide 15 an efficient plug of the kind stated, having a few, relative simple parts, which can readily be assembled, and which may be easily removed and replaced when they become broken or disordered.

20 The invention also has for its object to provide a double-gap spark plug which is compact and conforms to the present standard type of spark plugs.

Other objects and advantages of the invention will be pointed out in the detailed description appearing hereinafter, and in order that the same may be better understood reference is had to the accompanying drawing, in which—

30 Figure 1 is an elevation of the plug; Fig. 2 is a central vertical section thereof, and Fig. 3 is a cross section on the line 3—3 of Fig. 1.

Referring specifically to the drawing, 5 35 denotes the usual porcelain body of the plug, the same being fitted at one end into a metallic base shell 6 of standard shape, and having a reduced threaded end to screw into the engine cylinder. The upper end of 40 the shell is formed with a stuffing box which receives a gland 7. That portion of the plug 5 which is in the stuffing box has a shoulder 8 which seats against a washer 9 in the bottom of the stuffing box, and between the 45 shoulder and the inner end of the gland is interposed a washer 10. The shell 6 has two sparking terminals 11 at the cylinder end, whereby wear is distributed between two points. The gland 7 securely holds the plug 5 in the shell 6, and leakage of gas is effectively prevented by the washers 9 and 10.

Extending through the upper part of the plug 5 is a terminal rod 12, and fitting in a recess at the top of the plug is an adjusting 55 nut 14 for moving the rod in the direction of its length. This nut is cemented into, or

otherwise fixed in the recess, and any adjustment of the rod is made by turning the latter, it being threaded through the nut. Over the nut 14, and fitting against a shoulder on the plug 5 is a cap 15 through which the upper end of the rod 12 passes, and above said cap, the rod carries a jam nut 16, which latter, when it is screwed down against the cap, locks the rod in adjusted position.

The cap 15 has a depending marginal flange 17 provided at the bottom, at diametrically opposite points, with inturned segments 18 which seat in grooves 19 in the 70 sides of the plug 5. Between the grooves 19, the sides of the plug are flattened, as indicated at 20. The segments 18 slide over the flattened portions of the plug, and they are seated in the grooves 19 by giving the 75 cap a quarter turn, and after the nut 16 is screwed down, the cap is prevented from turning further on the plug, so that the rod 12 is now securely held even if the nut 14 should get loose.

In the lower part of the plug 5, in axial alinement with the rod 12, is mounted the second terminal rod 21. A shoulder or abutment 22 on the upper end of the rod 21 85 seats in a recess in the plug, and this shoulder is made small enough to pass through a longitudinal hole 23 in the upper end of the plug, in which hole the rod 12 seats, and thus, the rod 21 may be pushed through the 90 hole 23 from the top of the plug when the parts are assembled. Around the rod 21, at the bottom or cylinder end of the plug 5, is mounted an asbestos washer 24 over which is placed a brass washer 25 which packs the former over the opening 26 in the plug in 95 which the rod 21 seats, and prevents escape of any compression. A nut 27 screwed on the rod 21 holds the brass washer 25 to the packing washer. The parts also serve as an abutment to prevent upward movement of 100 the rod 12 in the plug.

In the upper end of the plug 5 is a transverse sight opening 28 closed at its ends by some suitable transparent material 29. This opening is located to render visible the adjacent ends of the rods 12 and 21 in order that the sparking therebetween may be observed. The opening may be horizontal or inclined, in which latter position the sparks may be observed without stooping over the 110 cylinder to look into the opening.

To assemble the parts, the lower terminal

rod 21 is pushed down through the openings 23 and 26 until the shoulder 22 seats in the recess in the plug 5. The washers 24 and 25 are then applied, and the nut 27 is screwed 5 on tight. The upper terminal rod 12 is next pushed through the opening 23, and the distance between the spark points of the two rods is adjusted by turning the upper rod in the nut 14. After the nut 14 is secured 10 in the recess 13, the cap 15 is put in place and the jam nut 16 is screwed down thereon. The plug 5 is then placed in the shell 6 and secured therein by the gland 7. The transparent closures 29 of the opening 28 are 15 cemented or secured in any other suitable manner to prevent any external explosions and to make the device fireproof.

In use, one of the wires of the ignition circuit will be connected to the outer end 20 of the upper terminal rod 12. The current passing through this rod jumps the gap between the lower end thereof and the adjacent upper end of the lower terminal rod 21. The spark thus produced at the gap may be 25 readily observed at the opening 28, thus indicating whether sparking is taking place at the inner terminals 11. The device therefore has the function of a spark plug and a tester, and it will instantly locate trouble 30 in the ignition system.

The form and construction of the device conforms to that of the present standard spark plugs, and the object sought is attained without the use of auxiliary wires, 35 connections, etc. The structure is simple and compact, and any broken or disordered parts can be readily removed and replaced. The manner of securing the two terminal rods effectually prevents relative longitudinal movement thereof to disturb the adjustment, the upper rod being securely held 40 against downward movement and the lower rod against upward movement.

I claim:

45 1. A spark plug having a body of insulating material provided with a transverse sight opening, axially alined upper and lower terminal rods mounted in said body, the adjacent ends of the rods extending into 50 the opening and being spaced to produce a

spark gap therein, a nut fixed on the outer end of the body through which nut the upper rod is threaded for longitudinal adjustment, said end of the body having a recess in which the nut seats, a cap mounted on 55 the outer end of the body over the nut, said cap having a depending marginal flange provided with diametrically opposite in-turned ends, and the side of the body having grooves in which said inturned ends seat 60 between which grooves the side of the body is flattened, a jam nut on the upper rod screwed against the cap, and means for locking the lower rod against movement longitudinally in either direction. 65

2. A spark plug having an integral body of insulating material provided with a transverse sight opening, axially alined upper and lower terminal rods mounted in 70 said body, the adjacent ends of the rods extending into the opening and being spaced to produce a spark gap therein, means for adjusting the upper rod longitudinally, an abutment on the lower rod, the body having a recess in which the abutment seats and a 75 longitudinal opening above said recess in which the upper rod seats, the width of the abutment being not greater than the diameter of said opening, and an abutment on the lower rod engaging the inner end of the 80 body.

3. A spark plug having an integral body of insulating material provided with a transverse sight opening, axially alined upper and lower terminal rods mounted in 85 said body, the adjacent ends of the rods extending into the opening and being spaced to produce a spark gap therein, and an abutment on the lower rod, the body having a recess in which the abutment seats and a 90 longitudinal opening above the said recess in which the upper rod seats, the width of the abutment being not greater than the diameter of said opening. 95

In testimony whereof I affix my signature in the presence of two witnesses.

EDMUND L. SUESS.
